[57] CLAIM

The ornamental design for a putty scraper, as shown and described.

DESCRIPTION

FIG. 1 is a top plan view of a putty scraper showing my new design;

FIG. 2 is a front elevational view thereof;

FIG. 3 is a side elevational view as seen from the right of FIG. 2;

FIG. 4 is a rear elevational view thereof;

FIG. 5 is a bottom plan view thereof;

FIG. 6 is a top plan view of a second embodiment of the design shown in FIG. 1, the only difference residing in the appearance of the scraping blade edge;

FIG. 7 is a front elevational view thereof;

FIG. 8 is a side elevational view as seen from the right of FIG. 7;

FIG. 9 is a rear elevational view thereof;

FIG. 10 is a bottom plan view thereof;

FIG. 11 is a sectional view thereof taken along line 11—11 of FIG. 9; and,

FIG. 12 is a sectional view thereof taken along line 12—12 of FIG. 9.
